(57) **CLAIM**

The ornamental design for a vehicle steering wheel, as shown and described.

DESCRIPTION

FIG. 1 is a front view thereof;

FIG. 2 is a left side view thereof;

FIG. 3 is a top perspective view thereof;

FIG. 4 is a left perspective view thereof;

FIG. 5 is a right perspective view thereof;

FIG. 6 is a close up perspective view of a portion of the left side of the vehicle steering wheel taken from FIG. 1; and, FIG. 7 is a close up perspective view of the knobs on the steering wheel taken from FIG. 4.

The broken lines depict the limits of the enlarged view and form no part of the claimed design.
